UNITED STATES PATENT OFFICE.

RICHARD BOCK, OF PRAGUE-SMICHOW, AUSTRIA-HUNGARY.

CONTINUOUSLY-OPERATING DRYING AND CARBONIZING KILN.

No. 891,456.

Specification of Letters Patent. Patented June 23, 1908.

Application filed November 7, 1907. Serial No. 401,146.

To all whom it may concern:

Be it known that I, RICHARD BOCK, of Prague-Smichow, in Bohemia, Austria-Hungary, a subject of the Emperor of Austria-Hungary, have invented certain new and useful Improvements in Continuously-Operating Drying and Carbonizing Kilns; and I do hereby declare the following to be a full, clear, and exact description of the invention, such as will enable others skilled in the art to which it appertains to make and use the same; reference being had, to the accompanying drawings, and to letters or figures of reference marked thereon, which form a part of this specification.

This invention relates to improvements in continuously operating kilns in which adjacent chambers, through which the material to be treated is conveyed by an endless car- rier, communicate alternately at the top and bottom, and the object of the invention is to provide an apparatus particularly adapted to the drying and carbonizing of soluble binding material in briquets and to prevent the burning or combustion of materials to be treated or handled at high temperatures.

In the drawings accompanying and forming part of this specification I have shown in detail certain advantageous forms of embodiment of the invention which, to enable those skilled in the art to practice the same, will be set forth in detail in the following description while the novelty of the invention will be included in the claims succeeding said description.

In said drawings—Figure 1 is a vertical longitudinal section of one form of kiln especially designed for carrying into effect the objects of the invention; Fig. 2 a horizontal section on line $y-y$ of Fig. 1 and Figs. 3 and 4 are vertical sections through the cooling conduits of kilns having modified forms of cooling devices.

Corresponding and like parts are referred to in the following description and indicated in the several views of the drawings by the same reference characters.

Kilns constructed according to this invention differ essentially from those already known in that the space traversed by the material comprises three subdivisions instead of two. In the first of these subdivisions the air is excluded and the material gradually heated, in the next of these a cooling of the material occurs without the aid of a current of air while in the third subdivision

the material is further cooled by the application of a cold air current. The gases or vapors may be drawn off by means of suitable partitions between the chambers and 60 conveyed away as may be necessary.

The kiln is divided in a well known manner into chambers a , a' and b , communicating alternately at the top and bottom. The material to be treated is conveyed in an 6 ascending and descending path by means of an endless conveyer such as chain c carrying suitable receptacles as d .

The kiln is divided into the above mentioned subdivisions and the chambers a and a' cut off from the outer air by contracted passages such as e being always closed by one or more of the receptacles d .

The chambers a are heated by hot gases which enter at a^3 and are conducted by flues f through said chambers and away from chamber a' in a direction opposite to that in which the receptacles d travel so that the material passing through said chambers is gradually heated.

Partitions g which divide the kiln into chambers are made hollow and serve to draw off the evolved vapors or gases, from the material being treated, through passages controlled by dampers such as h to a flue k .

The chamber a' not being heated by the hot gases which enter at a^3 , the temperature of the material in its passage therethrough is cooled and as said chamber is sealed from the atmosphere ignition of the material by contact with air is prevented. The material may be finally cooled in chamber b into which the outer air is admitted through loading and unloading opening o . This air travels through the subdivision in the opposite direction to that in which the material moves and escapes into the flue k through a passage controlled by damper p .

The cooling of the material in chamber a' may be effected by spraying water onto the material as illustrated in Fig. 3. This is accomplished by means of a spray-tube n preferably mounted beneath the hollow partition g so that sprays of water are projected onto the material in its downward and upward passage past the sprays. The steam or vapor formed by the contact of the water on the hot material passes off into flue k through a passage controlled by a damper l .

The temperature of the chamber may also be lowered as illustrated in Fig. 4. In this instance the hollow partition g is preferably

made of sheet metal and on the inside of said partition near the top thereof are placed sprinkling tubes n' . These tubes project streams of cold water against the sides of the flue walls which water flows down and passes out at the bottom through an opening o and is conducted off through a pipe, not shown, communicating with the opening.

I claim:

- 10 1. A kiln comprising a plurality of chambers alternately communicating at their tops and bottoms and having contracted passages formed at intervals in the walls of the chambers, an endless carrier movable through the chambers, and receptacles on the carrier forming a closure for the contracted passages.
- 15 2. A kiln comprising a plurality of heating chambers alternately communicating at their tops and bottoms, a cooling chamber connected with the heating chambers by a contracted passage, an endless carrier movable through the chambers and receptacles on the carrier forming a closure for the contracted passage.
- 20 3. A kiln comprising a plurality of sealed heating chambers alternately communicating at their tops and bottoms, a sealed cooling chamber connected with the heating chamber by a contracted passage, an endless carrier movable through said chambers, and receptacles on the carrier movable through said chambers, forming a closure for the contracted passage.
- 25 4. A kiln comprising a plurality of heating chambers alternately communicating at their tops and bottoms, and having a contracted entrance passage, a sealed cooling chamber connected with the heating chambers by a contracted passage, a chamber communicating with the air connected

to the cooling chamber by a contracted passage, an endless carrier movable through said chambers, and receptacles on the carrier forming closures for the contracted passages.

5. A kiln having a contracted entrance passage, hollow partitions dividing the kiln into a plurality of communicating chambers, a flue communicating with the partitions, means to conduct a heating medium from the central part of the kiln towards the entrance passage, a sealed cooling chamber connected with the inner heating chamber by a contracted passage, an air cooled chamber connected with the sealed chamber by a contracted passage an endless carrier movable through said chambers, and receptacles on the carrier forming closures for the contracted passages.

6. A kiln having a contracted entrance passage, hollow partitions depending from the top of the kiln forming a plurality of heating chambers, a heating flue leading from a central air intake and extending between the partitions, a sealed chamber connected with the heating chamber by a contracted passage, means to cool the sealed chamber, an air cooled chamber connected with the latter by a contracted passage, an endless carrier movable through said chambers, receptacles on the carrier forming closures for the contracted passages, a draft flue communicating with the partitions, and valved passages connecting the partitions and chambers.

In testimony that I claim the foregoing as my invention, I have signed my name in presence of two subscribing witnesses.

RICHARD BOCK.
